UNITED STATES PATENT OFFICE

JAMES H. SKITT, OF PHILADELPHIA, PENNSYLVANIA, ASSIGNOR TO SMITH, DRUM & COMPANY, OF PHILADELPHIA, PENNSYLVANIA, A CORPORATION OF PENNSYLVANIA

SUPPORT FOR IRONING MACHINE ROLLS

Application filed January 21, 1930. Serial No. 422,297.

The present invention relates to ironing machines and more particularly to an improvement in roll support and roll pressure control.

Some of the objects of the present invention are to provide an improved pressure controlled means for rolls of flat work ironers and the like; to provide a roll support wherein provision is made for holding the ironing roll out of contact with the ironing bed; to provide a roll supporting means wherein it becomes impossible for the roll padding to become injured through contact with the ironing bed; to provide a roll pressure control wherein successive increases of ironing pressure automatically take place as the ironing roll is moved away from the heating bed by the thickness of material being ironed; to provide means for successively subjecting goods being pressed to the weight of an ironing roll and the weight of an ironing roll plus spring pressure; and to provide other improvements as will hereinafter appear.

In the accompanying drawings Fig. 1 represents a side elevation of an ironing machine embodying one form of the present invention; Fig. 2 represents an end elevation of the same partly broken away; Fig. 3 represents an enlarged detail of an end of one of the ironing rolls and its pressure control shown in ironing position with the roll held out of contact with the steam chest; Fig. 4 represents the detail of Fig. 3 with the parts in position to apply the weight of the roll to the goods being pressed; Fig. 5 represents the detail of Fig. 3 with the parts in position to apply spring pressure to the roll; and Fig. 6 represents a detail of an end of an ironing roll with a modified form of pressure control.

Referring to the drawings and more particularly to Fig. 1, an ironing machine is illustrated generally of the type having side frames 10 spaced apart to receive and support between them a steam chest 11 and co-operating ironing roll 12, which latter forms one of a number of such rolls since these machines are more generally constructed with a plurality of ironing rolls. Since the roll supporting mechanism and pressure control means of the invention is the same at

opposite ends of the same roll, and is merely duplicated for each additional roll used, the present description will be confined to one end of one roll for the sake of brevity and clearness.

In the present construction the end of the roll shaft 13 is journalled in a bearing block 14 which is mounted for vertical sliding movement within a guide slot 15 formed in the upper portion of a lift rail 16 by means of which all of the ironing rolls can be moved simultaneously from one position to another. In connection with the slot 15 it should be noted that the bottom thereof is preferably provided with a stop 17 which is arranged to limit the downward travel of the journal block 14 and thereby definitely fix the lowermost position of the roll with respect to the steam chest 11. As here shown the block 14 has a depending lug 18 which is arranged to seat upon the stop 17 when journal block 14 reaches its lowermost position and preferably this lowermost position is such as to prevent actual contact of the ironing roll with the face of the steam chest 11.

As a means for lifting and maintaining the ironing roll 12 out of contact with the steam chest 11, a bolt 20 is provided which is fastened at its lower end to the block 14 and extends vertically upward to terminate in a threaded portion for the reception of a nut 21 and lock nut 22. This bolt 20 has, as a support, a follower 23 which is arranged to ride freely upon the bolt 20 and has a seat 24 to receive the upper end of a coil spring 25. The lower end of the coil spring 25 rests in a circumferential seat 26 formed in a second follower 27 also slidably mounted upon the bolt 20 but having a diameter greater than the width of the slot 15 so that it can rest upon the rail 16 in certain positions of the parts and thereby cause the block 14 to be yieldingly suspended upon its bolt 20. The initial set compression of the spring 25 is such as to overcome the weight of the ironing roll 12 and hold it normally in close proximity to the steam chest 11, but actually out of contact therewith, so under all conditions of operation there is no danger of the padding

of the roll becoming scorched through contact with the steam chest 11.

In order that the full weight of the roll 12 can be applied to the goods during the ironing operation and the spring suspension become ineffective, the block 14 is provided on its upper end with a boss 30 which has an upward path of movement intercepting the follower 27. In floating position of the roll 12 the top of the boss 30 is spaced from the bottom face of the follower 27 a predetermined distance to allow an initial upward movement of the roll before its full weight becomes effective upon the goods, and this construction also facilitates the easy feeding of the goods under the roll. When the roll has been lifted to bring the boss 30 against the follower 27 any further movement upwardly of the roll will lift the follower 27 from the rail 16 and thereupon the spring is rendered inoperative in so far as any spring lifting of the roll is concerned. It will thus be evident that the full weight of the roll is automatically brought into action at the exact time needed and simultaneously spring lifting action ceases.

For the purpose of supplementing the pressure upon the goods due only to the weight of the roll, a means is provided whereby the spring 25 again comes into operation but not as a lifting means but as a pressure means, the force of which is added to the weight of the roll 12. In the present instance the construction whereby this function is carried out consists of a cap 31 supported upon the upper face of the follower 23 and enclosing the upper end of the bolt 20, though the height of the cap is such as to leave a predetermined clearance space between the end of the bolt 20 and the inner face 32 of the cap 31. Outwardly projecting side webs 33 are preferably formed upon the cap 31 to maintain it in proper coaxial relation with respect to the bolt 20. A stud stop 34 is threaded through the top of a closure 35 in coaxial relation with respect to the cap 31 and carries a locking nut 36 by which the stud 34 can be locked in any desired set position. Normally the set position of the stud 34 is one spaced from the top of the cap 31 and this clearance allows for upward movement of the parts during the time the weight of the roll only is applied to the goods and when the cap 31 reaches the point where it is desired to bring additional pressure to bear upon the roll 12, it contacts with the end of the stud 34 so that further movement thereof upwardly is prevented. Since the closure 35 is fastened by studs 37 to the rail 16, it will be seen that, when the cap 31 is prevented from further upward movement by the stop 34, any further upward movement of the follower 27 will place the spring 25 under compression and this supplemental pressure then be added to the weight of the roll to more effectively press the goods.

In the form of the invention shown in Fig. 6 the lifting spring 25 bears against a double seated follower 38 the hub of which encircles the bolt 20 and supports the sleeve 40, also about the bolt 20 and receives on its upper end the nut 21 by which the bolt 20 is held suspended. The modification as so far described functions in precisely the manner of the spring lifting means of the first form of the invention, since the follower 27 normally seats upon the frame rail 16 and hence becomes a fixed abutment against which the spring 25 is compressed to act through the follower 38 and sleeve 40 to push the bolt 20 upwardly and thereby hold the ironing roll 12 out of contact with the steam chest 11. As a means for supplementing the weight of the roll 12 to give an increased ironing pressure when necessary, the upper side of the follower 38 forms a seat for the lower end of a second coil spring 41 which encircles the sleeve 40 and bears at its upper end against a thrust follower 42 which is free to slide upon the sleeve 38.

In order to regulate the pressure of the coil spring 41 the closure or housing 35 has its upper end provided with threaded holes 43 to receive adjusting screws 44 which project inside of the housing 35 and in the path of movement of the thrust follower 42. These screws 44 are normally set out of contact with the thrust follower 42 so as to leave a clearance space to allow a predetermined upward movement of the thrust follower 42 before any compressive action is placed upon the coil spring 41.

In the operation of this form of the invention the ironing roll 12 is held spaced from the steam chest 11 a predetermined distance through the action of the coil spring 25 acting upwardly against the follower 38 by reason of the fixed relation of the bottom follower 27. This upward pressure of the spring is transmitted through the sleeve 40 to the nut 21 and so holds the bolt 20 suspended and the journal blocks 14 in the position required to give the desired spaced setting of the ironing roll. During the ironing operation the ironing roll 12 rises away from the steam chest and the journal blocks 14, through the medium of the bosses 30, lift the follower 27 and thereby utilize the action of the spring 25 and the entire weight of the roll thus acts upon the goods being pressed. A further lifting of the roll eventually brings the thrust follower 42 against the screws 44 and thereupon the upper spring 41 comes under compression.

From the foregoing it will be apparent that a novel spring pressure control has been devised for the rolls of ironing machines and wherein springs are provided to normally maintain the roll out of contact with the steam chest but which are automatically rendered ineffective when the roll reaches a pre-

determined lifted position. Again upon the roll reaching another predetermined position the springs automatically become effective again but this time operating to increase the pressure of the roll instead of opposing such pressure. In the case of the modified form of the invention a second set of springs functions to supplement the pressure upon the roll, though these springs are initially inactive until the roll has reached a certain lifted position.

When it is desired to lift all of the rolls away from the steam chest the side rails 16 can be raised through operation of the rods 45 by the motion of eccentrics 46 actuated by a shaft 47, gears 48, under control of the hand wheel 50.

Having thus described my invention, I claim:

1. In an ironing machine, the combination of a steam chest, an ironing roll, means including springs for holding said roll out of contact with said chest, means to cause said springs to urge said roll toward the chest at a predetermined lifted position of the roll, and means to vary the position of operation of said last means.

2. In an ironing machine, the combination of a steam chest, an ironing roll, means including springs acting counter to the weight of said roll for supporting said roll in predetermined relation with said steam chest, means to cause said springs to urge said roll toward the chest at a predetermined lifted position of the roll, and means to vary the position of operation of said last means.

3. In an ironing machine the combination of side rails, an ironing roll slidably mounted thereon, rod members for suspending said roll, means including springs for supporting said members, followers respectively seated upon said rails for taking the thrust of said springs, and means movable with said roll for lifting said followers from said rails, whereby in a predetermined position of said roll the action of said springs is neutralized.

4. In an ironing machine, the combination of side rails, an ironing roll slidably mounted thereon, rod members for suspending said roll, followers respectively seated upon said rails, springs respectively seated upon said followers, a second set of followers respectively seated on said springs and supporting said rod members with said springs under compression, means movable with said ironing roll for lifting said first followers off of said rails to neutralize the action of said springs, and abutment means in the path of said second followers and operative in a predetermined lifted position of said roll to transmit the pressure of said springs in the opposite direction to the initial pressure of said springs.

5. In an ironing machine the combination of a steam chest, an ironing roll, springs

coacting with a fixed part to support said roll spaced from said chest, and means moving with said roll and operative in a predetermined lifted position of said roll to lift said springs from said fixed part, whereby said springs are rendered ineffective and the weight of said roll acts solely upon the goods being ironed.

6. In an ironing machine the combination of a steam chest, an ironing roll, springs coacting with a fixed part to support said roll spaced from said chest, means moving with said roll and operative in a predetermined lifted position of said roll to lift said springs from said fixed part whereby said springs are rendered ineffective and the weight of said roll acts solely upon the goods being ironed, and means brought into operation at another predetermined lifted position of said roll to cause said springs to resist further upward movement and thereby supplement the weight of said roll.

Signed at Philadelphia, county of Philadelphia, State of Pennsylvania, this 13th day of January 1930.

JAMES H. SKITT.
